UNITED STATES PATENT OFFICE.

GEORGE M. COKE, OF MILWAUKEE, WISCONSIN, ASSIGNOR TO THE FULLER-WARREN CO.,
OF MILWAUKEE, WISCONSIN, A CORPORATION OF WISCONSIN.

DESIGN FOR A STOVE.

No. 39,160.

Specification for Design.

Patented Feb. 25, 1908.

Application filed December 12, 1907. Serial No. 406,240. Term of patent 7 years.

To all whom it may concern:

Be it known that I, GEORGE M. COKE, a citizen of the United States, residing at Milwaukee, in the county of Milwaukee and State of Wisconsin, have invented a new, original, and ornamental Design for Stoves, of which the following is a specification, reference being had to the accompanying drawing, forming a part thereof.

Figure 1 is a front and partial side view in

perspective of a stove, showing my new design, and Fig. 2 is a rear elevation of the stove.

I claim:

The ornamental design for a stove, as shown.

GEORGE M. COKE.
